UNITED STATES PATENT OFFICE.

AUGUST F. RADANT, OF WAUSAU, WISCONSIN.

FEED MECHANISM FOR SAW-MILL CARRIAGES.

SPECIFICATION forming part of Letters Patent No. 367,235, dated July 26, 1887.

Application filed June 13, 1885. Serial No. 168,567. (No model.)

To all whom it may concern:

Be it known that I, AUGUST F. RADANT, of Wausau, in the county of Marathon, and in the State of Wisconsin, have invented certain new and useful Improvements in Feed Mechanisms for Saw-Mill Carriages; and I do hereby declare that the following is a full, clear, and exact description thereof.

My invention relates to feed mechanism for saw-mills, and will be fully described hereinafter.

In the drawings, Figure 1 is a side view of my device. Fig. 2 is an end view, and Fig. 3 is a plain view.

15 A is the base of my machine.

A' are standards that rise from the base, and are provided with bearings *a a* for a shaft, B, upon which is provided a frame, B', in which latter are journaled near one end a shaft, C, and near the other a shaft, C'. The frame B' is a hollow rectangle.

20 D D' are friction pulleys or wheels that are hung between the sides of the frame on shafts C and C', respectively, and D² and D³ are belt-pulleys that are keyed onto the outer ends of the shafts C and C', respectively.

25 E is the driving-pulley, E' the driving-shaft, and E² an idler, and F is a belt that passes over pulley E, under pulley D², over pulley D³, and under the idler E².

30 The pulleys D and D' are preferably faced with paper, and are so situated that when the frame B' is level they hang over but out of contact with a large pulley, G, that is keyed to a shaft, G', and hangs between the sides of the base A.

35 One end of frame B' is pivoted to a standard, H, the lower end of which fits in a socket, *h*, on the base A. This standard is made with a yoke, H', the rear of which rests against the end of the base, and which is provided with lugs *h' h'*, in which are pivoted cogged segments *h³ h⁴*, respectively, and between these segments is pivoted between lugs *i*, that are secured to the end of the base A, (one on each side of yoke H'), a double-faced cogged segment *k*, from which a shaft, K, extends through a bearing on the frame, and to this is keyed a hand-lever, K'.

40 The operation of my device is as follows: The shaft G' is revolved through pulley G, and carries a pinion, G², on its outer end for mesh with a rack on one of the beams of a carrier, L. (Shown partly in Fig. 2, with the parts in the

position shown in Fig. 1.) The pulleys D D', which are belted to turn in opposite directions, are out of contact with the pulley G, and therefore their revolution would not affect it; but when the frame B' is tipped, so that either of the pulleys D or D' will come in contact with pulley G, then the latter will be revolved. The tipping of the frame B' is accomplished by means of the lever K', shaft K, and segments *h³ h⁴*, as follows: Suppose the carriage L is to be retracted in a direction opposite to that indicated by the large arrow, Fig. 1, the handle K' is turned out of a vertical and toward the machine. This, through the segments *h³ h⁴* and *k*, will depress standard H, and through that end of frame B', and bring pulley D' into contact with pulley G, and as pinion G² meshes with a rack on the under side of one of the sills of carriage L, the carriage will be propelled backward, and then, when a cut is to be made, the lever is drawn away from the machine and pulley D, instead of D', makes contact with pulley G and the carriage is advanced. I make the pulleys D² and D³ of unequal diameters, the pulley D² being larger than pulley D³, so that when pulley G is being driven by pulley D' it will carry the carriage back rapidly, to be moved slowly forward when pulley D comes in contact. The bearings of shaft B are made adjustable to facilitate the centering of the frame B'. 85

Having thus fully described my invention, what I claim as new, and desire to secure by Letters Patent, is—

In saw-mill feed mechanism, the combination, with a suitable base and standards, of a shaft supported by the latter, and a rectangular tilting frame carried by said shaft, a vertically-movable end standard pivoted at its upper end to said tilting frame, a pulley keyed to the feed-shaft, and friction-pulleys belted to run in opposite directions and supported within the rectangular tilting frame just above and normally out of contact with the pulley on the feed-shaft, substantially as set forth. 95

In testimony that I claim the foregoing I have hereunto set my hand, at Milwaukee, in the county of Milwaukee and State of Wisconsin, in the presence of two witnesses.

AUGUST F. RADANT.
